WILBUR J. WATSON, OF EAST CLEVELAND, OHIO.

CENTERING FOR CONCRETE OR MASONRY ARCHES.

1,071,118.

Specification of Letters Patent.

Patented Aug. 26, 1913.

Application filed January 27, 1911. Serial No. 604,974.

To all whom it may concern:

Be it known that I, WILBUR J. WATSON, a citizen of the United States, residing at East Cleveland, in the county of Cuyahoga and State of Ohio, have invented a certain new and useful Improvement in Centering for Concrete or Masonry Arches, of which the following is a full, clear, and exact description.

10 This invention relates to improvements in centerings for concrete or masonry arches and particularly for long span arch bridges.

One of the objects of the invention is to lessen the cost of construction and erection 15 of centerings and to provide a centering which can be used repeatedly.

A further object is to provide a centering which has a minimum deflection when the load is applied and which is especially 20 adapted for situations requiring a large unobstructed opening for the flow of water or to avoid the obstruction of navigation in case the bridge is to be constructed over a navigable stream.

25 The centering constructed in accordance with my invention consists of an arch which is of the three-point-pin type and is composed of two sections suitably constructed, and connected together at their upper ends 30 in the center plane of the arch by a single pin, and at their lower ends, the said sections are each connected by a single pin to a suitable support, which I term a shoe.

35 The invention may be further briefly summarized as consisting in certain novel details of construction and combinations and arrangements of parts which will be described in the specification and set forth in the appended claim.

40 In the accompanying sheet of drawings, the single figure is a side elevation of a concrete arch bridge with my improved centering, or temporary false-work in position.

45 Referring now to the drawing, 10 represents the two abutments or piers for the concrete arch bridge 11 which is supported until set or until self supporting by my improved centering. On the inner faces of the abutments 10 are bases 12 for the centering, 50 which bases may be formed of masonry either integral with or independent of the abutments or may be formed by cantalivering steel beams out from the abutments.

55 The centering or false work which I employ consists of two braced arches 13, each of which is preferably formed of steel or

combined steel and timber and the whole structure being of what I term the "three-point-pinned type," inasmuch as it consists of two unitary sections 13^a, 13^b, which are pinned together at their upper ends or at the top of the arch 13 by means of a pin 14 and at their lower ends are connected by pins 15 to ordinary bridge shoes 16 which rest upon lowering devices, each section being connected at its lower end by a single pin to one of the shoes 16. It is to be understood that these pins 14 and 15 at the top and lower ends of the sections are not for hinging purposes, as the sections are not at any time intended to be moved inwardly or outwardly with respect to each other, but the two pinned sections are employed not only for convenience in the erection and removal of the centering but the pins confine the stresses which are transmitted between the two sections and between the lower ends of the sections and the shoes 16 to the three points. Each of the sections 13^a consists of a straight lower chord 17, a series of comparatively short upper chords 18 and a plurality of bracing members 19 arranged between the upper and lower chords. On top of the arches 13 and arranged at regular intervals are cross beams 20 on which are placed bows 21 formed preferably of timber and on top of the bows is laid lagging 22 upon which the concrete of the main arch 11 is placed.

After the concrete arch has set, and is self supporting, it is desirable, if not necessary, that the centering be lowered from the concrete arch as a unit, so that the arch can gradually assume its permanent position, it being understood that when the centering is removed, the arch settles a small amount, the exact amount depending upon the design and span of the arch. Consequently, between the shoes 16 and the abutments 12, I provide suitable lowering devices, each of which may be designated as a whole by the reference character 23. These lowering devices do not constitute parts of the present invention, and need not be explained in detail, nor further illustrated. It will be understood that there will be employed appropriate lowering devices which will enable the entire centering to be lowered gradually and uniformly.

I may, if desired, employ steel tie rods 28 between the lower ends of each of the arches 13, but except in special cases, these

tie rods need not be employed for the reason that the abutments 10 are built to take care of the horizontal thrust of the centering arches 13.

- 5 In the erection of the centering and in the construction of the concrete arch, after the abutments 10 and bases 12 have been constructed, the lowering devices will be placed in position, after which the two sections of
 10 the centering arch will be erected or assembled. After the cross beams, bows and lagging are in position, the concrete or masonry arch 11 is built, this arch being preferably built in sections. Preferably the top sections
 15 11^a and 11^b of the arch 11 are first placed in position in order that the centering frames will be brought to a good bearing. Then the sections at the quarter points are placed in position and afterward the
 20 other sections are placed in position in a predetermined order.

After the concrete arch has been built and the centering has been left in position, the required length of time to enable the arch 25 to obtain sufficient strength to be self supporting, the centering is lowered in the manner above stated. The centering may then be removed from the site of the bridge and used again for similar structures at other
 30 locations.

The character of the steel or steel and timber arches 13 is such that as the load is applied to them, there is a minimum deflection,

the stresses being carried principally by the top chord members. This is an extremely 35 desirable feature for this class of work. Furthermore, not only is the deflection very slight, but the character of the centering is such that a large open space is left below the concrete arch for the flow of water, 40 the level of which is indicated by the line 29. Furthermore, the centering need not obstruct or interfere with navigation, in view of the fact that at least at the center of the stream, the distance from the normal 45 water level to the centering is almost the same as to the concrete arch itself.

Having thus described my invention, what I claim is:—

A centering or temporary false work for 50 masonry or concrete arches comprising a three-point-pinned arch composed of two sections supported solely at their lower ends and connected together at their upper ends at the center plane of the arch by a single 55 pin through which stresses are transmitted from one section to the other, supports at the lower ends of the two sections each connected to the corresponding section by a single pin.

In testimony whereof, I hereunto affix my signature in the presence of two witnesses.

WILBUR J. WATSON.
